ABSTRACT

A paper bobbin of a cylindrical or tubular form covered with a thin paper. This bobbin has grooves or one slit running along the length of the tube. This paper bobbin can be used for heat-treatment of yarn in cheese form. It collapses and contracts in its periphery length when a cheese is heated. The pressure caused by thermal shrinking of wound yarn causes the paper tube to collapse with ease. The collapsed shape of the paper tube in a cheese is round or heart-like.

PAPER TUBE BOBBIN FOR TREATMENT OF YARN IN CHEESE FORM

The present invention relates to a paper tube bobbin used for heat-treatment of yarn in a cheese form. There have hitherto been known two processes for heat-treatment of a heat shrinkable yarn; one is to treat it in hank form and the other is to treat it in cone or cheese form in which a yarn is wound on a bobbin.

Heat-treatment of yarn in hank can surely be expected to produce the balanced effect of heat-treatment. However, the increase of equipment and workers for processes before and after the heat-treatment can not be avoided. Moreover, this procedure is apt to distort and entangle the yarn and cause breakage of yarn in rewinding, knitting and weaving. It also spoils the quality of the final product.

When the yarn is heat-treated in a cheese or a cone form, the cost of heat-treatment is extremely low in comparison with that of hank form treatment. When the heat-treatment is applied to the yarn in cheese form, perfect shrinkage of the yarn at inner layers tends to be hindered or made flat by the shrinking pressure, and sufficiently bulky yarn can not be obtained.

Various bobbins have been devised whereby the outer circumference of a bobbin itself shortens in accordance with the shrinking of yarn. This kind of bobbin known previously is made of metal or synthetic resin. An elastic bobbin covered with elastic sponge material has also been used for the same purpose.

A metallic bobbin tends to corrode by hot water or steam, and has inevitably to be of complex structure and is inconvenient for use. Another defect of a metal bobbin is that it is too expensive to throw it away after it is used.

A bobbin made of synthetic resin tends to undergo a change in its form by heat and pressure applied during heat-treatment. The distortion of and permanent deformation of a synthetic resin bobbin made it difficult to reuse the bobbin. Irregular deformation of the bobbin reduces efficiency of the rewinding process and other forwarding process after the heat-treatment and spoils the quality of treated yarn.

Usually, a paper bobbin has a tubular structure. A paper tube bobbin of thin paper collapses easily with the shrinking of yarn layer. Paper is not expensive material for making a bobbin compared with metal or plastics material, and has a proper solidity and elasticity. However, if the shape of the collapsed bobbin is not almost circular but irregular and serrated, it will cause entanglement of yarn in a cheese, and cause breaking of yarn in the rewinding process. It is confirmed by our study that to make a paper tube bobbin thinner only in order to make it collapse to a uniform shape in a cheese is not sufficient to make a good bobbin. That is, if the material of the bobbin is made weaker, it collapses with the shrinking of heat-shrinkable yarn wound on the paper tube when treated with heat, resulting in a complex shape having such an indented cross section as shown in FIG. 4A and disturbance of the yarn wound near the surface of the bobbin. A lot of yarn breaks will be caused in the process of winding from this bobbin to the other for shipment or dyeing, with the efficiency of rewinding lowered and quality of yarn deteriorated greatly.

The object of the present invention lies in presenting a novel paper tube bobbin for heat-treatment of yarn

in cheese form, and to show the way to use such paper tube bobbin. The present invention offers a profitable method for thermosetting twisted yarn and for heat-treatment or bulking of spun yarn, textured yarn and filamentary yarn. The present invention also aims at simplification of yarn processing and accomplishing the production of yarn with better yarn quality. The present paper tube bobbin can be thrown away after use.

In the present invention, a paper bobbin comprises a cylindrical or tubular structure made of formed paper material which has a narrow groove or a plurality of grooves or an oblique cut slit running straight along the length of said structure, and the outer surface of the structure is covered at least over the vicinity of said groove or slit with thin paper. This paper tube bobbin collapses easily at the notch or at the slit and shortens its circumference receiving the pressure caused by the shrinkage of heat-shrinkable yarn wound on it when heat-treated. The shape of the collapsed bobbin is mostly heart-shape or round-shape. The form of collapsed structure like this has substantially no irregular indented shape over the outer circumference of the paper bobbin when collapsed. Therefore, the inner layer yarn is hardly disturbed because of the simple shape of the collapsed bobbin in spite of the collapse of a part of the bobbin itself. Thin paper covering the surface of the tube structure is not stuck with paste around the slit or groove. A preferable thickness of thin paper is 0.05 – 0.2 mm., considerably thin compared with the thickness of the bobbin. For example, kraft paper is suitable. The size of paper tube bobbin can be determined in accordance with the amount of yarn taken up, bobbin holder of winder and the width of traversing of winder. In case the amount of yarn is 300 g – 2,000 g, a diameter of the outer circumference of the bobbin is 40 mm – 100 mm and the length of it is 5 – 10 inches. The thickness of paper constructing the cylindrical structure relates to a diameter of the paper tube bobbin and 1.00 mm – 4.00 mm is appropriate. A preferable thickness is determined by the quality of paper material and percentage of thermal shrinkage of yarn. The depth of the groove should be between one third to four fifths of the thickness of the paper material. Width of the groove is preferably less than 5 mm. The ideal size of a diameter in a collapsed state after heat-treatment is arithmetically calculated referring to the percentage of shrinkage of yarn in boiling water. In the drawing, model pictures and important structure of the present bobbin parts are emphasized more or less. FIG. 1A represents a cylindrical or tubular form used for a base structure for making a paper tube bobbin.

FIG. 2A represents an example of the present invention showing a slit cutting across obliquely to the diameter of the cylindrical structure.

FIG. 2B is a top view of the cylindrical structure of FIG. 2A.

FIG. 2C shows the cylindrical structure of FIG. 2A in a collapsed condition.

FIGS. 3A, 3B, and 3C show different embodiments of the bobbin.

FIG. 3A shows an embodiment in which the bobbin has a part of its surface adjacent the slit covered with paper.

FIG. 3B shows another embodiment in which the bobbin has its entire surface covered with paper.

FIG. 3C shows another embodiment in which the bobbin has its surface covered with one kind of paper

and the faces of the slit covered with a different kind of paper.

FIG. 3D shows the bobbin of FIG. 3B in a collapsed condition.

FIG. 4A shows the shape of the bobbin with yarn wound thereon prior to heat treatment.

FIG. 4B shows the same bobbin collapsed after heat treatment.

FIGS. 1A and B represent a shaped cylindrical structure made of a thick paper. The cylindrical or tubular structure *a* is a round shape with a hollowed part *b*. This structure has a shape just like what has usually been used as a paper tube bobbin for taking up of the yarn. The spindle of a take-up winder is inserted into the hollowed part to wind up yarn.

An example of the present paper tube bobbin is shown in FIGS. 2A, 2B and 2C. Characteristic feature of this example is a slit cutting obliquely across the thickness of the tubular structure running straight along a supposed longitudinal axis in length wise direction as shown in FIGS. 2A & B. If heat-shrinkable yarn wound on this paper tube bobbin is treated with heat, one edge of the slit slides into the other edge along the cut face, and shortens the outer circumference of the bobbin which remains nearly round in shape. This type of collapse causes the least disturbance of yarn. FIGS. 2A, and 2B are a perspective view and cross section view of a tubular structure with a slit *f* which is cutting the tubular structure across the thickness in an oblique manner. As shown in the cross-section view in FIG. 2B, a slit *f* is cut along the length of paper cylinder, crossing the thickness of the cylinder obliquely to the diameter of the round-shaped section of the cylindrical structure. Accordingly, the edge *g* is adjacent to the edge *h* at the slit section with faces neatly contacted. FIG. 2C shows the collapsed structure after use. Edge *g* slides inside edge *h* and the outer circumference contracts in a nearly round manner by the pressure caused by the shrinking of yarn layer. An appropriate angle of inclination of the slit cutting the thickness of the structure is between 30° to 60° to the diameter of the cylindrical structure. If a thin paper *p'* of a kind different from kraft paper constructing cylindrical structure is put between two faces of the edges of the slit, as shown in FIG. 3C or if both edges are coated with silicon, teflon, the edges can slide more smoothly. Covering the slit with thin paper like kraft paper prevents the disturbance of inner layer yarn as shown in FIG. 4A and 4B.

As shown in the FIGS. 3A & B, the whole or a part of surface of the tube structure is covered with kraft paper *p* stuck with paste except at least the surface *i* (diameter × percentage of shrinkage × 3 × 1/2) of one edge *g* which slides inward the bobbin. *j* is the pasted part fixing the paper on the tube structure. FIG. 3(C) shows a tube structure wherein the outside paper covering extends beyond one edge which will facilitate movement during heat treatment of the wound yarn. FIG. 3D shows the section of the collapsed tube of FIG. 3B. The function of part *i* where thin paper is not stuck is to decrease resistance against the contraction of the circumference and to be effective for bobbin to contract keeping a round shape when the outer circumference shortens with the heat-treatment of the heat-shrinkable yarn wound on the paper tube bobbin as stated before. Therefore, this makes rewinding quite easy without any disturbance of yarn layers.

The cylindrical structure or tube structure of the present invention consists of paper material made from natural or synthetic fiber. Such fiber material may be waste paper, wood pulp, bamboo pulp, cotton linter, fibrous flakes, non-woven fabric, sliver of fibrous material, pieces of regenerated paper and the like. As the methods of making the bobbin, such the following generally-known methods can be named; to roll a thick paper and fix the shape, to pile adequate sheets of thin paper and fix the shape with starch, or to mix the shredded pieces of fiber material or waste paper with size (e.g. starch, C.M.C., P.V.A., glue, etc.) and pour the mixture into a mold to be dried up. The last named method of using a mold is the most simple and cheapest. This method is advantageous because the compression strength of the tube can be chosen from a wide range.

As stated above, paper tube bobbin of the present invention is effective in twist setting of yarn made of any fibers. It can also be applied to heat treat the heat-shrinkable yarn made of synthetic fiber materials in the form of cheese. For example, bulking of spun yarn of acrylic fiber or thermo-setting of textured yarn can be accomplished with low processing cost without spoiling the yarn quality. As a result, supply of bulky yarn for fabric making factory and dyeing factory is streamlined and heat-treatment of yarn without hank reeling process realized.

For instance, bulking of spun yarn at spinning mill can be performed economically by taking up to the collapsible bobbin of this invention, and after cheeses up, bulk it by treating with steam heat. It can be shipped after being wound up in a cheese or cone form or sent to a dyeing plant. Perforated dyeing tube is used to wind the yarn up when cone or cheese dyeing is performed. The cheese can be sent to a dyeing plant and after being bulked in cheese form, dye it after rewinding the yarn into a cone or cheese style.

Thus, collapsible bobbin of the present invention makes it possible for yarn to be processed in a cheese form throughout spinning, dyeing, and finishing processes, thereby lowering of the processing cost due to omission of some preparatory work can be accomplished.

Example 1

800 g of spun yarn of 1/60 (Nm) which is of 100 percent acrylic fiber having 25 percent of shrinkage by 100°C steam treatment was wound up on a collapsible paper tube bobbin and prepared a cheese with wound density of 0.24 g/cm³. The paper tube was prepared by shaping a paper tube structure and cutting a slit along its entire length direction, the slit cutting across the thickness of the tube structure with an angle of 55° to the diameter of the tube structure. The outer diameter of the tube structure was 60 mm, the length 172 mm, the thickness of paper 2 mm. Kraft paper of 0.03 mm thickness covered the outer surface of the paper tube structure, and stuck with paste except the both sides of the cut slit line in 4 cm width. The cheese was treated with steam of 100°C for 10 minutes. Then the outer diameter was reduced to about 45 mm in an almost circle shape. The disturbance of the inner layer yarn was small. And the yarn was not broken in rewinding. This steam treated yarn was packed 50 kg. in weight in a cardboard case, the whole weight of the cases totaling 10 tons. Said 10 tons yarn was transported from a spin-

ning plant to a dyeing plant, where the yarn was wound on to conical perforated dyeing tube of polypropylene for cone dyeing. 800 g yarn was wound for each cone. The winding speed was 450 m/min. and winding density was 0.18 g/cm with wound weight of 800 g. 100 kg yarn per one dyeing lot was dyed to a dark, or a middle, or a light color, totaling in weight 10 tons. After ordinary oiling, the cones were dried, Milano rib stitch were knit with the tubular knitting machine of 18 GG. by supplying directly from the dyed cone. In this case, the following is the comparison of the process for producing the same product by hank dyeing with the present invention as to the necessary personnel for the process from cheese-up at a spinning plant to the knitting at a knitting mill. Hank dyeing process needs 884 workers for 8 hours per day work, while the method of the present invention 584 workers for the same hours. This shows how the necessary labor can be reduced as compared with the conventional method. Of course there was found no change in the handling of knitting and the 20 feeling after knitting between the method of the present invention and the conventional process.

Example 2

Acrylic filament yarn of 200 denier/68 filaments with 12.5 percent shrinkage by 110°C steam was wound on a collapsible paper tube bobbin, made mainly of cellulose, having the thickness of 1.5 mm, the outer diameter 70 mm, and the length 220 mm. A slit line, whose angle to a tangent line of the outer circumference of 30 the structure was 40°, was running along the longwise side, and the surface of the paper tube structure was covered with 0.03 mm paper, stuck with paste except the both sides of said cutting line by 2 cm in width. 1,000 g per bobbin of said yarn was taken to a cheese 35 with 0.45 g yarn/cm³ density. Then the cheese was treated with steam of 110°C for 20 minutes, and the percentage of shrinkage was measured. The percentage of shrinkage of the inner, middle, and outer layer were 12.5 percent, 12.7 percent and 12.4 percent respectively. The shrinkage of yarn was almost the same value. The paper bobbin contracted to almost a round shape in cross section with about 60 mm in circumference and no disturbance of the inner layer yarn was observed.

Example 3

The same collapsible paper tube bobbin as that of Ex-

ample 2 was used. The yarn was of polyester filaments 120 denier/40 filaments, (percentage of shrinkage by hot water was 13 percent). The yarn weighting 800 g was wound on a cheese with 0.55 g/cm³ of density. The cheese was treated with steam at 130°C for 20 minutes. The shrinkage of the yarn, of the inner, middle, and outer layers of the cheese was 12.2 percent, 12.1 percent, and 12.2 percent respectively. The paper bobbin contracts to an almost round shape with 55 mm diameter on an average without disturbance of the inner layer yarn. The yarn of the inner, middle, and outer layers was knit alternatively, and then was dyed with Foron Navy S-GL (Sandoz) 3 percent owf at 100°C for 60 minutes. There were no appreciable color differences among the inner, middle, and outer layer sample yarns when observed with the naked eyes. Accordingly, heat setting of polyester filament yarn was attained uniformly by steaming a cheese with use of the collapsible paper tube bobbin of the present invention.

What is claimed is:

1. A paper tubular bobbin for heat treatment of yarn in cheese form, comprising
a shaped tubular form of paper having a thickness of 1.00-4.00 mm and
a slit cutting the thickness of the paper in an oblique manner wherein
at least a part of the outside surface of said form around and over said slit is overlapped with thin paper, said thin paper being connected to said form on opposite sides of said slit and being unconnected in the region adjacent said slit so as to permit circumferential contraction of the form adjacent said slit and to maintain the outer shape of said bobbin during heat treatment of yarn.
2. A paper tubular bobbin according to claim 1, wherein said thin paper is Kraft paper and overlaps the entire paper surface of the tubular form.
3. A paper tubular bobbin according to claim 1, wherein said slit is across the thickness of the paper to intersect the diameter of the cross section at an angle of 30° - 60°.
4. A paper tubular bobbin according to claim 1, wherein the tubular form is shaped by molding.
